UNITED STATES PATENT OFFICE

EARL F. OYSTER, OF CLEVELAND HEIGHTS, OHIO, ASSIGNOR TO THE OSBORN MANUFACTURING COMPANY, OF CLEVELAND, OHIO, A CORPORATION OF OHIO

JOLT SQUEEZE STRIPPER LATCH

Application filed September 14, 1931. Serial No. 562,659.

This invention relates to molding machines and particularly to an improved latch for a jolt squeeze stripper. In the field of jolt squeeze stripper molding machines, it is quite common to use dogs or latches to hold the lifting frame up as it returns from the squeeze position and thus keep the mold in an elevated position while the pattern is drawn downward and out of the mold. A common defect in all of the machines now on the market, is that the dogs jolt against the rods in which they engage during the jolting action and this materially increases the wear on the dogs and the consequent maintenance cost. The purpose of this machine is to provide a latch and operating mechanism therefor which will automatically engage the lifting frame during the drawing operation, but which can be quickly withdrawn from engagement therewith and positively held out of engagement during the jolting operation, the movement of this latch being such as not to interfere in any manner with the operation of the machine. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a front elevation showing the application of the latch mechanism to a down draw molding machine, shown in the jolting position; Fig. 2 is a plan view approximately on the line 2—2 of Fig. 1; Fig. 3 is a partial front elevation of the latch mechanism with the machine in the squeeze position; Fig. 4 is a view similar to Fig. 3 showing the parts in the draw position; Fig. 5 is a view similar to Fig. 3 showing the parts moving down toward the draw position; and Fig. 6 is an enlargement in front elevation of the locking mechanism in the position of Fig. 1.

As will be seen from Fig. 1, the latch mechanism embodying the invention is adapted

to be mounted on a jolt squeeze stripper molding machine of conventional type adapted for down draw and having a base 1 supporting a table 2 by a squeeze cylinder 3 and draw cylinders 4. A jolt cylinder 5 is contained within the squeeze cylinder. The machine is adapted for the usual cycle of molding operations which includes squeezing the mold (not shown) upward against a stationary squeeze head such as 6.

The table supporting elements 11 of the latch mechanism are duplicated on each side of the machine, but in the preferred embodiment herein illustrated it is not necessary to have the entire mechanism repeated on each side.

Each latch comprises a vertical supporting arm 11 or 11' keyed to a shaft 12 or 12' which in turn is carried in suitable fixed bearings 13 or 13' in a bracket 14 or 14' on the machine frame. Each arm 11 and 11' is preferably made adjustable for height by a two piece construction with interengaging teeth, as indicated at 15. The arm is extended outwardly at the top, as at 16, this extension carrying a roller 17 and serving to bring the roller, when in the position of Fig. 4, directly above the shaft 12. The left latch also carries locking and releasing features which are not repeated on the right latch for the reason that the two latches are connected by a link 20 for common motion in opposite directions, as best seen in Fig. 1, which shows the link pivoted at its left end to a short downwardly directed arm 21 also keyed to the shaft 12 and on the right side to a short upwardly directed arm 21' also keyed to the shaft 12'.

This link 20 is movable to the right by means of a compression spring 22 which bears at its opposite ends against abutments on the link and on the machine base, respectively, this being a convenient means for giving the arms 11 and 11' a constant tendency toward the position of Figs. 3 and 4. The amplitude of the motion of the arms 11 and 11' may be regulated by any convenient means, the preferred form being a stop screw 23 also carried by the link and adapted to bear against a stop 24 on the machine frame.

The locking means and the releasing means

for the entire latch mechanism form a part of the left latch only. This left latch mechanism comprises the arms 11 and 21, already mentioned, also a locking arm 30 and a releasing arm 31, all the arms being fast upon the shaft 12. For convenience in construction and attachment the locking arm 30 and the link arm 21 are made as a unitary bell crank. The locking arm extends inward, and the releasing arm downward and inward. The locking arm 30 carries a movable nose 40 on its outer end, this nose being pivoted as at 41 and having a rearward upper extension 42 overlying the outer end of the arm 30 and urged away therefrom by a compression spring 43 partly housed in said extension. The motion imparted to the nose by the spring is limited by a lug 44 on the bottom of the nose, which lug is stopped against an abutment 45 on the lower side of the arm 30. The nose is rounded off near the upper end of its front face as indicated at 46 and has a top bearing lug 47. A catch 48 is fast to the left front of the squeeze cylinder top to hold down the arm 30, as shown, in the position of Fig. 1 and Fig. 6. In case the catch is far enough down to interfere with the nose 40 when the arm 30 is being lowered, the rounded face 46 rides on the vertical edge of the catch, and the entire nose tilts back, as shown in Fig. 5, compressing the spring 43. This arrangement enables the lug 47 to snap under the bottom of the catch 48 in any relative positions of nose and catch, and avoids the need of any synchronization of the motion of the squeeze cylinder with that of the latch mechanism.

The operation of this latch is as follows:

Starting with the table in the position of Fig. 1, the mold is filled with sand and jolted as usual. In this position the squeeze piston is down and of course does not participate in the jolting motion. The catch 48 holds the locking arm 30 down and the supporting arms 11 and 11' in the retracted position shown in Fig. 1, within and out of contact with the ends of the table lifting frame 18 and also below and out of contact with the table 2, with the result that the jolting motion is not communicated to the latch mechanism. As the table is raised to the squeeze position, Fig. 3, the latch spring 22 expands, moving the link 20 to the right, thus moving the arms 11 and 11' outward to their respective vertical positions beneath the lifting frame as illustrated in Fig. 3 for the arm 11. Upon completion of the squeeze the frame and table are lowered to the draw position, Fig. 4, in which the frame rests on the arms 11 and 11'.

To let the frame and table down from the draw position, Fig. 4, to return to the starting and finishing position, Fig. 1, thus completing the cycle of table positions to get ready for the next mold the operator steps on the treadle 32. Since this treadle is keyed to

the shaft 12, the treadle motion moves both arms 11 and 11' inward toward the position of Fig. 1. It will be noted that in Fig. 3 the point of tangency of the rollers 17 with the bottom surface of the lifting frame is directly in line with the center of the shaft 12 and 12', respectively. Thus the inward motion of the rollers 17 has no lifting component whatever and the only effort to be exerted upon the treadle is the overcoming of friction, so that the operation of the treadle does not call for an excessive muscular effort and its operation during an entire working day does not unduly fatigue the operator.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. A jolt squeeze stripper latch comprising an arm adapted when in vertical position to support a jolt table, automatic means constraining said arm to said vertical position, non-automatic means adapted to move said arm out of said position, and automatic locking means adapted to hold said arm out of supporting position when the table is in jolting position, said locking means comprising a lug attached to the squeeze cylinder, an arm positively connected to said supporting arm, and an extension carried by said last-named arm, said extension being engageable beneath said lug when the squeeze cylinder is down.

2. Latch mechanism for a molding machine of the type having a jolt table and a squeeze piston, said mechanism comprising a pair of arms pivoted beneath the sides of the jolt table for movement to a vertical position to support said table and to an inclined position beneath and out of contact with said table, link mechanism for moving said arms simultaneously, means constantly tending to move said link mechanism to spread said arms, means operable to overcome said spreading tendency and to move said arms to the inclined position, a lug vertically movable with the squeeze piston and a locking arm carried in fixed relation to one of said supporting arms for coaction with said lug, said locking arm including an extension member retractable to pass one portion of said lug and extendable to catch beneath another portion of said lug when said lug is in bottom position.

3. Latch mechanism for a molding machine comprising a pair of arms pivoted beneath the sides of the jolt table for movement to a vertical position to support said table and to an inclined position beneath and out of contact with said table, a link connecting said

arms on opposite sides of their respective pivots, a spring tending to move said link in one direction to spread said arms, means operable to move said link against the tendency of said spring and to move said arms to the inclined position, and locking means carried by another arm in fixed angular relation to one of said supporting arms for co-action with a catch on the machine, said locking means including a nose engageable under said catch in a limit position of the catch, and movable yieldingly along said catch in intermediate positions of the catch.

4. Means for supporting the jolt table of a molding machine when in draw position comprising a pair of latches mounted on opposite sides of the molding machine and means for simultaneously moving said latches into and out of a table-supporting position, said moving means comprising a connecting link between said latches extending across the machine, a spring connected to said link and to the machine base tending to move said link to bring said latches into table-supporting position, a stop between said link and said machine base, each of said latches comprising an arm adapted to carry the jolt table when brought into supporting position, one of said latches also comprising a second arm rigid with relation to the first-named arm and means adapted to engage said second arm and thereby to hold said first-named arms out of table-supporting position, said last-named latch also including a lever to move latches in opposition to the tendency of said spring.

5. In a jolt squeeze machine, a jolt table, a lug movable with the squeeze cylinder, a table supporting latch comprising an arm adapted to be brought into or moved out of supporting engagement beneath said table, another arm rigidly related to said first-named arm and pivoted in common therewith, a nose pivoted to the free end of said second named arm, means constantly urging said nose into a position to underlie said lug when the squeeze cylinder is in down position and thereby to hold said first-named arm out of table-supporting position, and a side surface on said lug along which said nose is adapted to ride yieldingly prior to snapping thereunder.

Signed by me this 8th day of September, 1931.

EARL F. OYSTER.
